UNITED STATES PATENT OFFICE.

ADELBERT F. PARKER, OF OGDEN, UTAH; WYNNE M. PARKER ADMINISTRATOR OF THE SAID ADELBERT F. PARKER, DECEASED.

BALANCED PUMP.

Application filed January 9, 1923. Serial No. 611,584.

The present invention relates to improvements in pumps, and has for its object to provide a device of this character which can be utilized for pumping any kind of a liquid or gaseous medium, and which embodies novel features of construction, whereby a high degree of efficiency is obtained, and the surges, back lash or water hammer occurring in the discharge pipe are absorbed and dissipated so that but little of such sudden shocks is felt on the power unit operating the pump.

Among the objects of the invention is to provide a pump which embodies novel balancing means, whereby the internal pressures caused by the head against which the pump is acting are equalized at all positions of the pump whether the pump is working or at rest. This avoids the necessity of using extra power to overcome this pressure head when operating the pump, and enables the pump to be operated by the use of just a sufficient amount of power to overcome inertia and friction and to elevate the fluid being pumped from the source of supply to the height of the pump. There is thus no waste of energy in overcoming the pressure in the column at the pump outlet, and the pump can be operated with the expenditure of a minimum amount of power.

By making appropriate modifications in the details of construction, the idea can be embodied in any of the conventional forms of pumps, and for illustrative purposes the invention is shown on the drawings and described in the specification as embodied in a vertical type of pump. It will be understood, however, that I do not restrict myself to the exact details of construction which have been illustrated on the drawings for the purpose of disclosing the idea of the invention, since the invention is susceptible of many different embodiments, and many modifications and changes can be made within the scope of the claims without departing from the spirit of the invention.

For a full understanding of the invention reference is to be had to the following description and accompanying drawings in which,

Figure 1 is a top plan view of a vertical type of pump which is constructed in accordance with the invention.

Figure 2 is a vertical sectional view

through the pump on the line 2—2 of Figure 1.

Figure 3 is a vertical sectional view through the pump on the line 3—3 of Figure 1.

Figure 4 is a vertical sectional view through the pump on the line 4—4 of Figure 1.

Corresponding and like parts are referred to in the following description and indicated on all of the views of the drawings by like reference characters.

A vertical type of the pump which embodies the invention is illustrated by Figures 1 to 4 inclusive of the drawings. This is a duplex pump and has two operating units which are similar and complementary in construction, being arranged side by side so that they discharge through a common outlet pipe, thereby giving a substantially continuous outflow of water. Each of the units includes a pair of spaced and parallel upright cylinders, the cylinders of one unit being designated by the reference numerals 1 and 2, and the corresponding cylinders of the other unit being designated by the reference numerals 3 and 4. One of the units is shown in detail by Figure 3, while the other unit is shown in detail by Figure 4. Cylinder 1 of the unit shown by Figure 3 corresponds to the cylinder 3 of the unit shown by Figure 4, while the cylinder 2 of Figure 3 corresponds to the cylinder 4 of Figure 4. All four of the cylinders are connected at the top and communicate with an upwardly extending outlet pipe 5. Associated with the outlet pipe 5 is a conventional air dome 6 which operates in the usual manner to assist in obtaining an even flow of water through the outlet.

Mounted within each of the cylinders 1 and 3 is a pair of pistons 7 and 8, said pistons being both provided with upwardly opening check valves 9. Extending upwardly from the respective pistons 7 and 8 are the piston rods 10 and 11, the piston rod 10 of the upper piston having a tubular formation and slidably receiving the piston rod 11 of the lower piston. The lower end of the tubular piston rod 10 is suitably connected as by means of a bail 12 to the upper piston 7, and the upper end thereof is provided with a transversely disposed slotted bracket 13 which slidably receives a pin 14 at one end of a lever 14. This lever 14 is

preferably mounted at its middle point upon a vertically slidable fulcrum rod 15, and the opposite end thereof is provided with a pin 14^b slidably engaging a transversely slotted bracket 16 which is applied to a vertical piston rod 17, said piston rod extending upwardly from a solid piston 18, one of which is mounted within each of the balancing cylinders 2 and 4. The pistons 18 and 7 of each unit of the pump are thus connected in such a manner as to move equal distances in opposite directions as the lever 14 is oscillated about its central pivot point.

The piston rod 11 of the lower piston 8 is provided at its upper end with a transversely slotted bracket 19 which slidably receives a pin 20^a at one end of a lever 20. The opposite end of this lever 20 is provided with a pin 20^b which slidably engages a transversely slotted bracket 21 which is applied to the piston rod 17 of the balancing piston 18. An intermediate portion of this upper lever 20 is provided with a pivot pin 22, which is slidably received within a transversely slotted bracket 23 at the upper end of the fulcrum rod 15. The two arms of this upper lever 20 are different in length, so that the two pistons connected by the lever will have different movements.

30 The mounting and connection of the levers is such that the two working pistons 7 and 8 are close together when at the limit of their downward stroke, as indicated by Figure 3, while they are separated at the limit of their 35 upward stroke, as indicated by Figure 4. The fulcrum rod 15 also has an up and down movement, and the ultimate result of the connection between the pistons is that the balancing piston 18 has one increment of 40 movement, while the upper working piston 7 has three increments of movement, and the lower working piston 8 has two increments of movement.

45 The fulcrum rod 15 and the piston rod 17 of the balancing piston are each provided with transversely slotted cross heads 24. The slots of these cross heads slidably receive crank pins 25 which are rigid with gear wheels 26, and arranged thereon in such a 50 manner as to move the fulcrum rod 15 and piston rod 17 in opposite directions. The two gear wheels 26 mesh with a gear wheel 27 on a drive shaft 28, said drive shaft being shown as provided with a balance wheel 29. 55 The system of gearing is duplicated for each unit of the pump, and the arrangement is such that the fulcrum rod 15 and piston rod 17 have the same increment of movement but move in opposite directions as the pump is operated. The balancing piston 18 moves in an opposite direction to the working pistons and, as previously mentioned, the balancing piston has one increment of movement on each stroke, the lower working piston 8, two increments of movement, and the

upper working piston 7, three increments of movement. The balancing piston 18 is a solid piston, while the two working pistons 7 and 8 are each provided with the upwardly opening check valves 9.

The upper ends of all of the cylinders are in communication with each other and with the outlet pipe 5, and the arrangement is such that the head of the water or fluid against which the pump is acting presses upon the balancing piston 18 in the balancing cylinders 2 and 4, and also upon that one of the working pistons 7 and 8 in the working cylinders 1 and 3 which happens to have the valves 9 thereof closed. The cylinders and pistons all have substantially the same cross sectional area, so that the pressure head caused by the column of water in the outlet pipe acts upon the two sets of pistons and causes them to practically counterbalance each other. So far as the actual amount of pressure is concerned, the working pistons are always substantially counterbalanced by the balancing pistons, so that the only force necessary to operate the pump is that which is required to overcome friction and inertia and lift the fresh supply of water from below.

50 In the operation of this type of pump it must be kept in mind that the balancing pistons 18 each have one increment of movement, the upper working pistons 7, three increments of movement, and the lower working pistons 8, two increments of movement. As the balancing piston 18 of one unit of the duplex pump moves upwardly from the position shown by Figure 4 to the position shown by Figure 3, the two working pistons 7 and 8 move downwardly from the position shown by Figure 4 to the position shown by Figure 3. During this downward movement of the pistons the valves 9 of the lower piston 8 are closed, while the valves 9 of the upper piston 7 are opened to permit the water which was previously in the space between the pistons to be forced upwardly through the upper piston 7 and into the space above the said upper piston. Upon the reverse or upward movement of the working pistons 7 and 8, the valves 9 of the upper piston 7 are closed, while the valves 9 of the lower piston 8 are opened, so that a fresh supply of water can be drawn into the space between the pistons. The water above the upper working piston 7 is moved upwardly. This piston 7 has three increments of movement, and for purposes of explanation it may be considered that three units of water are pumped. One of these three units of water passes over into the corresponding balancing cylinder to compensate for the downward movement of the balancing piston. A second of these three units of water passes over into the opposite side of the duplex pump, as will be herein-

after set forth, while the third of these three units of water is forced upwardly through the outlet pipe 5.

As indicated by Figures 1 and 2, the fulcrum rods 15 of the two units of the duplex pump are connected by a walking beam or lever 30, so that they always reciprocate in opposite directions. The working strokes of the two units of the duplex pump thus alternate with each other, so that the working pistons 7 and 8 of one unit of the pump are moving downwardly, while the working pistons of the other unit of the pump are moving upwardly. Upon the downward movement of the working pistons the upper working piston 7 has three increments of movement, so that three units of water must be supplied to compensate for the displacement of the piston. One unit of water is forced upwardly through the piston from the space between the two pistons, a second unit of water is carried over from the corresponding balancing cylinder, being forced over by the upward movement of the balancing piston, while the third unit of water is supplied from the opposite unit of the duplex pump. Upon the upward movement of the working pistons, three units of water are pumped, and as previously explained, one unit passes over into the corresponding balancing cylinder to compensate for the downward movement of the balancing piston, a second unit passes over into the working cylinder of the opposite unit of the duplex pump, while the third unit is forced upwardly through the discharge pipe. Each upward stroke of the working pistons of each unit of the duplex pump thus has a net pumping action of one unit of water. It will be noted, however, that at all positions of the pistons the pressure caused by the head of water against which the pump is acting is the same on the balancing pistons and the working pistons, so that the two sets of pistons are counterbalanced. A high degree of efficiency is thereby obtainable and the surges, back lash or water hammer occurring in the discharge pipe are absorbed and dissipated so that but little of such sudden shocks are felt on the power unit operating the pump.

Having thus described my invention what I claim as new and desire to secure by Letters Patent is,

1. A pump including a pair of working cylinders and a pair of balancing cylinders, a pair of working pistons mounted in each working cylinder, telescoping piston rods for the working pistons, a balancing piston mounted in each balancing cylinder, a piston rod for each balancing piston, separate lever connections between the piston rod of the balancing piston and the piston rods of the working pistons of each pair whereby the working pistons have a differential move-

ment, and means for causing the pressure due to the head against which the pump is operating to act upon the balancing pistons in such a manner as to counterbalance the pressure on the working pistons.

2. A pump including a pair of working cylinders and a pair of balancing cylinders, a pair of working pistons mounted in each working cylinder, a piston mounted in each balancing cylinder, movable fulcrum members, independent levers mounted upon the movable fulcrum members and operatively connecting the respective working pistons to the balancing piston of the respective pairs whereby the pistons have a differential movement, and means for causing the pressure due to the head against which the pump is operating to act upon the balancing piston in such a manner as to counterbalance the pressure on the working pistons.

3. A pump including a pair of working cylinders and a pair of balancing cylinders, a pair of working pistons mounted in each working cylinder, a balancing piston mounted in each balancing cylinder, a piston rod for each balancing piston, slidable fulcrum rods parallel to the piston rod, means for alternately reciprocating the piston rods and fulcrum rods in opposite directions, levers mounted upon the fulcrum rods and connecting the respective piston rods to the working pistons, and means for obtaining counterbalancing pressures on the balancing piston and the working pistons.

4. A pump including a pair of working cylinders, a pair of balancing cylinders, a pair of working pistons in each working cylinder, telescoping piston rods connected to the respective working pistons, a balancing piston mounted within each balancing cylinder, a piston rod connected to each balancing piston, reciprocating fulcrum rods arranged parallel to the piston rods, means for alternately reciprocating the fulcrum rods and piston rods of the respective balancing piston in equal and opposite directions, a pair of differential levers mounted upon each piston rod and operatively connecting the respective piston rod of the balancing piston to the respective piston rod of the working pistons whereby the working pistons have a differential movement, and means for causing the pressure due to the head against which the pump is operating to act with a counterbalancing effect on the balancing piston and working piston.

5. A pump comprising two sets of cylinders and their cooperating mechanism, each including a pair of cylinders arranged in a spaced and parallel relation to each other, a pair of working pistons mounted in one of the cylinders, a balancing piston mounted in the opposite cylinder, telescoping piston rods connected to the respective working pistons, a piston rod connected to the bal-

ancing piston, reciprocating fulcrum rods arranged parallel to the pistons, cross heads on the fulcrum rod and balancing piston rod respectively, oppositely rotating crank arms 5 engaging the respective cross heads to move the fulcrum rod and piston rod in equal and opposite directions, a pair of independent levers mounted upon the fulcrum rod and operatively connecting the balancing piston 10 rod to the piston rods of the respective working pistons whereby the pistons have a differential movement, and means for maintaining communication between the outlet and the two cylinders whereby a counterbalancing pressure is maintained at all times 15 between the working pistons and the balancing piston.

6. A pump comprising two sets of cylinders and their cooperating mechanism, each 20 including a pair of spaced and parallel cylinders, a pair of valved working pistons mounted within one of the cylinders and having a differential movement, whereby the pistons are brought together at one end of 25 their stroke and separated at the other end of their stroke, a balancing piston mounted within the other cylinder, an operative con-

nexion between the balancing piston and the two working pistons whereby the balancing piston has one increment of movement and 30 the working pistons two and three increments of movement respectively, the balancing piston and working pistons moving in opposite directions, and means for maintaining at all times communication between the 35 pump outlet and the two cylinders whereby there will be counterbalancing pressures on the balancing piston and working pistons.

7. In apparatus of the class described, the combination of four cylinders intercommunicating, a piston in each of said cylinders, means intercommunicating movement from the pistons, a second piston in some of said cylinders, means intercommunicating movement of the second pistons with that of some 40 of the first pistons, and means for effecting compensatory movement relative to all the pistons for causing some of the pistons to have three increments of movement while others have two increments of movement, 45 and still others have one increment of movement.

In testimony whereof I affix my signature.
ADELBERT F. PARKER.
